(57) **CLAIM**

The ornamental design for a display screen with icon or packaging with surface ornamentation, as shown and described.

DESCRIPTION

FIG. 1 is a front view of a first embodiment of a display screen with icon or packaging with surface ornamentation showing the new design; and,

FIG. 2 is a front view of a second embodiment of a display screen with icon or packaging with surface ornamentation showing the new design.

The broken lines are included for the purpose of illustrating environmental structure and form no part of the claimed design. Further, the design may be applied to any planar surface of a package.

1 Claim, 2 Drawing Sheets
